UNITED STATES PATENT OFFICE.

WILLIAM A. BATTEY, OF HAVERFORD, PENNSYLVANIA, ASSIGNOR TO PENNSYLVANIA CRUSHER COMPANY, OF NEW YORK, N. Y., A CORPORATION OF NEW YORK.

CRUSHER ROLL.

1,410,546.

Specification of Letters Patent. Patented Mar. 28, 1922.

Application filed December 17, 1920. Serial No. 431,437.

To all whom it may concern:

Be it known that I, WILLIAM A. BATTEY, a citizen of the United States, residing in Haverford, Montgomery County, Pennsylvania, have invented Crusher Rolls, of which the following is a specification.

This invention relates to machines for crushing or breaking coal, ore, etc., and has to do more particularly with improvements 10 in the construction of the rotary crushing roll of such a machine,—one object of said invention being to provide a novel form of sectional or built up roll involving relatively simple and substantial means for holding its 15 sections together, and for permitting their easy replacement when worn or broken.

Another object of the invention is to provide a roll of the above type with novel means for removably connecting its sections 20 or segments to supporting hubs, together with a novel device for spacing or holding apart said hubs, when the section-retaining means is set up or tightened.

I also desire to provide a sectional 25 crusher or breaker roll with means for facilitating the separation or disassembly of its parts.

These objects and other advantageous ends I attain as hereinafter set forth, reference 30 being had to the accompanying drawings, in which,

Fig. 1 is a longitudinal, vertical section of a crushing roll and its associated shaft constructed in accordance with my invention;

35 Fig. 2 is a transverse vertical section on the line 2—2; Fig. 1;

Fig. 3 is a longitudinal vertical section on a larger scale than Figs. 1 and 2, illustrating the detail construction of one of the sections 40 of the roll; and

Fig. 4 is a transverse vertical section on the line 4—4, Fig. 3.

In the above drawings, 1 represents a roll-supporting and driving shaft to which are 45 keyed or otherwise fixed a pair of hubs 2 having each a radially extending flange or plate portion 3, preferably of circular outline. Supported by these flanges is a series of any desired number of externally toothed 50 cylindrically curved segments 4, together constituting the barrel or body of a crushing roll and these segments are provided with outwardly projecting teeth or knobs which may be of any desired form and arrangement, there being also longitudinally ex-

tending ribs 4^a formed on the inner sides of said segments. These ribs serve to stiffen and otherwise strengthen the segments and while they are shown in detail in Figs. 3 and 4 they have been omitted from Fig. 1 to 60 avoid confusion. In the apparatus illustrated I have shown the teeth as in two sets of different lengths and sizes.

At or adjacent its ends, each segment is provided with inwardly extending lugs and 65 these lugs project immediately adjacent the outer face of the hub flange 3. Each of said lugs is provided with an opening, preferably cylindrical in outline, in line with a tapered opening in the adjacent flange 3 and dowels 70 7 extend through the opening in each of the lugs 8 into the adjacent openings in the hub flange, for which purpose they are cylindrically formed where they pass through the lugs 8 and are frusto conical where they 75 enter the opening of said flange. The dowels 7 for the lugs of each drum section 4 are in alignment and are made in tubular form for the reception of bolts 9 which extend through them and are threaded at their ends 80 for the reception of nuts.

In assembling the parts of the roll, the bolts 9 are inserted through the lugs 8 of the sections 4 and the flanges 3 of the hubs, which have been previously keyed in place 85 upon the shaft 1, and the dowels 7 are then placed on said bolts and inserted through the aligned pairs of holes of the flanges and lugs, after which the nuts on said bolts are set up to rigidly hold the dowels in the flanges 90 and thus retain the toothed sections 4 in their assembled positions.

In order to prevent the hubs approaching each other when the nuts on the bolts 9 are set up, I provide the adjacent faces of the 95 flanges 3 with two or more aligned holes for the reception of separator bars 10, whose ends are of reduced section so as to enter said holes while their body portions are shouldered to cause them to act as struts 100 between the flanges for the purpose noted.

In order to facilitate the disassembly of the roll or the removal of one or more of its toothed sections, I provide the bolts 9 with shoulders 11 adjacent the inner ends of the 105 dowels 7, so that after the nut has been removed at one end of any bolt, said end may be tapped with a light hammer, whereupon the shoulder adjacent the opposite end of the bolt will be caused to act upon the adjacent 110

dowel to force it out of the tapered hole in the flange 3. Thereafter the nut may be removed from the second end of the bolt and the opposite dowel may be similarly removed.

By the above construction I am enabled to build up a structurally strong, substantial crusher roll, any of whose sections may be quickly and conveniently removed or replaced in the event of breakage or wear of any of the teeth thereon.

While I have shown the sections of the roll as provided with teeth of different lengths, it is of course to be understood that the dimensions, numbers and arrangement of said teeth are immaterial, since the construction or form of the operating or active face of the roll or sections thereof is immaterial so far as the present invention is concerned.

20 I claim:

1. A crushing roll consisting of a supporting structure including a pair of hubs; a series of sections mounted on said hubs to form the body of the roll; means including dowels extending axially of the roll through said hubs and into the sections for holding them in position and retaining members extending into the dowels.

2. A crushing roll consisting of a supporting structure including a pair of hubs; a series of sections mounted on said hubs to form the body of the roll and each including inwardly extending lugs; with dowels extending through the lugs into the hubs and each having a frusto conical portion, for rigidly holding the sections in place.

3. A crushing roll consisting of a supporting structure including a pair of hubs; a series of sections mounted on said hubs to form the body of the roll and each including inwardly extending lugs; dowels extending through the lugs into the hubs for holding the sections in place; and bolts extending through the dowels of each section for holding them in position.

4. A crushing roll consisting of a pair of hubs; a series of sections mounted on said hubs to form the body of the roll and each having inwardly extending lugs; dowels extending through said lugs into the hubs and each having a tapered portion, with means for holding said dowels in place.

5. A crusher roll consisting of hubs each having a series of tapering holes therein; a series of sections mounted on said hubs to form the body of the roll and each having

inwardly projecting lugs provided with openings respectively in line with the holes of the hubs; tubular dowels extending through the lugs respectively and having tapering portions entering the holes of the hubs; with bolts extending through the dowels of each section for holding them in position.

6. A crushing roll consisting of supporting hubs; a series of sections mounted on the hubs to form the body of the roll and having lugs extending adjacent the hubs; means including tapered dowels for connecting the lugs to the hubs; and bolts for holding the dowels in place.

7. A crushing roll consisting of supporting hubs; a series of sections mounted on the hubs to form the body of the roll and having lugs extending adjacent the hubs; means including tapered dowels for connecting the lugs to the hubs; and bolts for holding the dowels in place, each of said bolts having at least one shoulder positioned to be driven against the smaller end of the dowel when this is to be removed.

8. A crushing roll consisting of a pair of hubs; a series of sections mounted on said hubs to form the body of the roll; means for holding said sections to the hubs including a series of axially extending bolts having means tending to draw the hubs together; with independent struts for limiting the movement of the hubs toward each other under the action of said bolts.

9. A crushing roll consisting of a pair of hubs; a series of sections mounted on said hubs to form the body of the roll; means for holding said sections to the hubs including a series of axially extending bolts having means tending to draw the hubs together; with means for limiting the movement of the hubs toward each other under the action of said bolts, consisting of shoulderered spacing bars mounted between said hubs.

10. The combination of a supporting shaft; two upwardly flanged hubs fixed thereon; a series of sections mounted upon the flanges of said hubs to form a substantially cylindrical body structure and each having inwardly projecting lugs extending adjacent the outer faces of the flanges respectively; members holding each of the lugs to its adjacent flange; and bolts for retaining said members in place.

WILLIAM A. BATTEY.
